act.

UNITED STATES PATENT OFFICE.

JACOB F. MEHREN, OF CHICAGO, ILLINOIS, ASSIGNOR TO JOHN F. WOLLENSAK, OF SAME PLACE.

TRAP-LOCK.

SPECIFICATION forming part of Letters Patent No. 372,923, dated November 8, 1887.

Application filed April 21, 1887. Serial No. 235,608. (No model.)

To all whom it may concern:

Be it known that I, JACOB F. MEHREN, of Chicago, in the county of Cook and State of Illinois, have invented a certain new and useful Improvement in Trap-Locks, of which the following is a specification.

Heretofore the trap-locks that have been practically used on fire or police alarm boxes have been adapted to be opened only by one key—viz., that furnished to citizens—which is trapped and held by the lock, and is disengaged by a key in the possession of a representative of the police or fire department, which latter key, however, is not itself capable of operating the lock.

The object of my invention is to provide a third key by which the box can be opened without trapping the key. This key will be in the hands of members of the police or fire department, and will enable them to open the box at any time without trapping the key and without the necessity of also using the master or releasing key.

In general my invention consists in such a relative construction of the third key and the operative parts of the trap-lock that the lock can be opened by such key without its being trapped. The invention is applicable to the various kinds of trap-locks, and the construction will of course be varied to meet the conditions of the particular character of trap-lock to which the invention may be applied.

The accompanying drawings illustrate the application of the invention to the more usual form of trap-lock; but it will be understood that my invention is not limited to the details of construction.

In the drawings, Figure 1 is an elevation of the parts of the lock when the bolt is thrown to lock the alarm box; Fig. 2, a similar view showing the bolt withdrawn, the citizens' key trapped thereby, and the release-key in position; Fig. 3, a section of the tumblers as raised by either key for operating the lock; Fig. 4, a side view of the bit end of the third key; Fig. 5, a similar view of the same key from the other side, and Fig. 6 an end view of this key.

The shell A of the lock contains the usual

spring-bolt, B, and the tumblers C. The tumblers have lugs a b, adapted to engage with a stud, c, on the bolt. The tumblers also have the usual curved surface, d, with which the bit of the citizens' key D engages to raise such tumblers and withdraw the bolt, and a slot, e, which engages the bit of the key D and traps it in the lock at the same time that the bolt is kept withdrawn, as shown in Fig. 2. The usual master or release key, E, engages the tails e' of the tumblers and raises them so as to release the bit of the key D from the slot e and permit the spring f to throw the bolt. This movement of the bolt turns the key D, releasing it from the slot e, and it can then be removed from the lock.

The key F has a bit similar to that of the key D, so that the tumblers can be raised by it and the bolt withdrawn; but the bit of this key F is provided with a lateral extension or wing, g, which is wider than the trapping-slot e in the tumblers, so that the bit cannot enter that slot and be trapped thereby.

The key F will raise the tumblers and withdraw the bolt like the key D; but the tumblers will not drop upon the bit of the key F when the slot e is reached, and hence the key F will not be trapped. The key F is used in the same key-hole as the key D, the key-hole being of course formed to admit the wing g; but it is evident that the key F may be made to act upon the tumblers through another key-hole and at a different point from the key D, in which case no wing on the bit of the key would be required, as will be well understood.

It is not intended to claim herein the particular construction shown in the application filed by John F. Wollensak for Letters Patent for trap-latch locks March 5, 1887, having Serial No. 229,775.

What I claim is—

1. In a trap-lock, the combination, with the tumblers and bolt thereof, of means for trapping the ordinary key, and another key constructed to operate the lock without trapping, substantially as set forth.

2. In a trap-lock, the combination, with the tumblers and bolt thereof, the tumblers being

provided with a slot engaging the bit of the ordinary key and trapping the same, of a key constructed to raise the tumblers and withdraw the bolt without engagement with said trapping-slot, substantially as set forth.

5 3. In a trap-lock, the combination, with bolt B and tumblers C, the latter having a trapping-slot, e, of a key, F, having a wing, g, on

its bit wider than said slot e, substantially as set forth.

This specification signed and witnessed this

18th day of April, 1887.

JACOB F. MEHREN.
